W. T. BOOTH,

TELEPHONE SET,

APPLICATION FILED APR. 24, 1917.

1,330,234.

Patented Feb. 10, 1920.

Inventor:
William T. Booth.
by *S. C. Munn*, Atty.

UNITED STATES PATENT OFFICE.

WILLIAM T. BOOTH, OF EAST ORANGE, NEW JERSEY, ASSIGNOR TO WESTERN ELECTRIC COMPANY, INCORPORATED, OF NEW YORK, N. Y., A CORPORATION OF NEW YORK.

TELEPHONE SET.

1,330,234.

Specification of Letters Patent. Patented Feb. 10, 1920.

Application filed April 24, 1917. Serial No. 164,234.

To all whom it may concern:

Be it known that I, WILLIAM T. BOOTH, a citizen of the United States, residing at East Orange, in the county of Essex and State 5 of New Jersey, have invented certain new and useful Improvements in Telephone Sets, of which the following is a full, clear, concise, and exact description.

This invention relates to telephone sets for 10 subscribers' stations, more particularly to those of the intercommunicating type, and has special reference to the ringing equipment provided in these sets.

In sets of the intercommunicating type, 15 there is usually provided a ringing key for each station on the line for which the set is intended. In view of the various capacities of different lines, this necessitates a large number of different sets, differing from each 20 other principally in the ringing equipment, and in order to make it possible to stock the sets for different capacity lines and at the same time not carry a prohibitive stock of the various types, the use of unit construction 25 has been resorted to. By this means a comparatively small stock of the various parts may be kept on hand, and sets to meet the various requirements may be supplied as desired.

It is the object of this invention to provide 30 an improved ringing unit for use in such a set, one that may be easily assembled within the set to provide the desired equipment and which, moreover, will be economical to manufacture and will present a good appearance in the assembled set.

To accomplish this object there is provided 35 a unit, designed to mount interchangeably back of the cover plate or housing of the set, and to be concealed by a combined 40 number plate and escutcheon through which the ringing buttons project. This escutcheon closes the opening provided for unequipped positions, concealing the circuit controlling 45 devices from view and thereby presenting a good appearance to the front of the set. The extended portions are slotted and adapted to receive number plates designating the lines 50 corresponding to the various ringing buttons.

The various features of this invention may 55 be more clearly understood by reference to the accompanying drawings, in which Figure 1 is a front view of a set equipped with two four-button units, a portion of the

escutcheon being removed to more clearly show the method of mounting these units; Fig. 2 is a perspective view of a four-button ringing unit removed from the set and with a ringing bar from a second unit in position 60 to show the method of joining the assembled units to provide a common ringing bar for all stations; and Fig. 3 is a side view showing more clearly the method of assembling the ringing springs. 65

In the front of the housing 4 there is provided an opening 5, suitable to accommodate the maximum number of buttons for which the set is designed. In the drawings there is shown a set suitable for a capacity up to 70 eight lines. The housing is provided with clearance holes 6, through which pass the screws 7 engaging threaded holes 8 in the mounting plate 9 of the assembled unit. Extensions of this mounting plate are 75 formed, as shown, to provide mounting brackets 10 to which is secured, by means of the screws 11, 11 the insulating plate 12 of fiber or a similar insulating material. Upon this plate are mounted the U-shaped springs 80 13, 13. The free ends of these springs are preferably saw-toothed to insure good contacts, and, by means of the insulating buttons 14, 14, may be forced into engagement with the ringing bar 15, which is common 85 to the individual ringing springs. In order to aid in properly lining up the ringing bars of adjacent units, and to eliminate the necessity for more than one ground connection, each ringing bar is provided with a lug 16, offset from the plane of the bar, approximately the thickness of the stock, and having a threaded hole 17. At the opposite end of each bar is a lug 18, adapted to fit within the recess in an adjoining bar formed by bending up the offset lug 16. The lugs 18 are provided with perforations 19, thereby allowing the parts when assembled to be locked together by means of the screw 20, which passes through 90 the clearance hole and into the offset lug. 95

On the front of the set there is provided a combined number plate and escutcheon 21, which is adapted not only to conceal the ringing units from view, thereby presenting 105 a good appearance to the set, but also to provide means for designating the various lines corresponding to the different ringing buttons which project through perforations in the central portion of this escutcheon. A 110

number of slightly different escutcheons are provided to correspond to the various capacities of the set upon which they may be used. In each case the escutcheon portion differs only in the number of perforations provided for the ringing buttons, and is adapted to entirely conceal the opening in the housing. Symmetrically located on either side of the escutcheon proper are the 10 card frame extensions, provided with the slots 22 opposite the buttons which they are to designate. These extensions are embossed slightly out of the plane of the escutcheon proper to provide space for inserting a designating card and a strip of celluloid or mica to protect the surface of this card.

It will be noted that the construction of the escutcheon plate makes possible the use 20 of a housing or cover plate for a different capacity line without requiring any additional drilling. In the drawings this equipment is shown as mounted on the housing of a non-flush type of set, but it will, of course, be understood that the construction 25 is adapted to apply equally well in connection with the cover plate of a flush type of set.

What is claimed is:

- 30 1. In a telephone set, the combination with a housing having an opening suitable for mounting the circuit controlling devices, of a plurality of ringing units each comprising a plurality of contact springs with coöperating buttons, and a ringing bar common to the springs of each unit having at one end a lug approximately flush with the bar and at the other end a lug off-set from the plane of the bar to provide means for 35 interlocking with the flush lug of an adjacent bar; means for connecting together adjoining ringing bars; means for interchangeably mounting said units on said housing; an escutcheon plate having a portion adapted to close the opening in said housing; perforations in said escutcheon plate through which project said buttons; and extended portions adapted to form card holders.
- 40 2. In a telephone set, the combination with a housing having an opening suitable

for mounting the circuit controlling devices, of a plurality of ringing units each comprising a plurality of contact springs with coöperating buttons, and a ringing bar common to the springs of each unit; means for 55 alining and interchangeably connecting together adjoining bars, said means comprising a lug approximately flush at one end of the bar and at the other end of the bar a lug off-set from the plane of the bar to provide means for interlocking with the flush lug of an adjacent bar; and means for interchangeably mounting said units on said housing.

3. In a telephone set, a plurality of ringing units each comprising a plurality of contact springs, buttons adapted to bear against the free ends of said springs whereby contact is made with a ringing bar common to the springs of each unit, connecting lugs at 70 either end of each of said bars, and interchangeable means for alining and joining together adjacent bars to provide a ringing bar common to the set.

4. In a telephone set, a ringing unit comprising 75 an insulating block having a plurality of contact springs mounted thereon, a mounting plate provided with angular extensions for fastening to said block, a ringing bar having at one end a lug approximately 80 flush with the bar, on the other end of said bar a lug offset from the plane of the bar to provide a means for interlocking with the flush lug of an adjacent bar, and a plurality of buttons projecting through 85 perforations in said mounting plate to engage the free ends of said springs whereby contact may be made with said ringing bar.

5. In a telephone set, a plurality of ringing units each comprising a plurality of contact springs, buttons adapted to bear against the free ends of said springs whereby contact is made with a ringing bar common to the springs of each unit, and interchangeable means for alining and joining together 95 adjacent bars to provide a ringing bar common to the set.

In witness whereof I hereunto subscribe my name this 20th day of April, A. D. 1917.

WILLIAM T. BOOTH.
